UNITED STATES PATENT OFFICE.

JOHN W. CULMER, OF CLEVELAND, OHIO, ASSIGNOR TO THE NATIONAL COMPUTING SCALE COMPANY, OF SAME PLACE.

DESIGN FOR A SCALE-FRAME.

SPECIFICATION forming part of Design No. 30,940, dated June 6, 1899.

Application filed May 12, 1899. Serial No. 716,587. Term of patent 14 years.

To all whom it may concern:

Be it known that I, JOHN W. CULMER, a citizen of the United States, residing at Cleveland, county of Cuyahoga, and State of Ohio, have invented and produced a new and original Design for Scale-Frames, of which the following is a specification, reference being had to the accompanying drawing, forming a part thereof.

10 The figure is a perspective view of a scale-frame constructed according to my design. The leading or material features of my design consist of a horizontal cylindrical case A, closed at both ends, two vertical bars B B, secured to the ends of said case, and a yoke C, consisting of two vertical bars c, which are fixed to the outer faces of the bars B B and extend below them, and the horizontal cross-bar c', which extends between and is united 15 with the lower ends of the bars c c and has a circular horizontal ring c² at its middle.

20

The drawing may be regarded as a view showing either side of the scale-frame, since both sides are alike.

In each side of the cylindrical case A, at diametrically opposite points, is a horizontal slot a, and a short vertical slot a' crosses said horizontal slot midway between its end. 25

Having described my invention, what I claim as new, and desire to secure by Letters Patent, is—

The design for a scale-frame as herein shown and described.

In testimony whereof I hereunto affix my signature in the presence of two witnesses. 35

JOHN W. CULMER.
